UNITED STATES PATENT OFFICE.

CONYERS BUTTON, OF PHILADELPHIA, PENNSYLVANIA.

DESIGN FOR STOCKING FABRIC.

Specification forming part of Design No. 6,666, dated May 27, 1873; application filed May 13, 1873.

To all whom it may concern:

Be it known that I, CONYERS BUTTON, of Philadelphia, Pennsylvania, have invented a Design for Stocking Fabric, of which the following is a specification:

My design for a stocking fabric, which is clearly illustrated by the figure in the accompanying drawing, consists of an arrangement of stripes A and B and narrow rib C upon a plain ground, *a*, each stripe A being composed of a series of narrow stripes or ribs, shaded in respect to each other so as to produce the peculiar blended appearance shown.

The stripe B is precisely similar to the stripe A, except that it is reversed.

Irrespective of the colors employed, I claim—

The design for a stocking fabric, substantially as described, and as represented in and by the accompanying drawing.

In testimony whereof I have signed my name to this specification in the presence of two subscribing witnesses.

CONYERS BUTTON.

Witnesses:

Wm. A. STEEL,
L. BOSWELL.
